DOOR LATCHING MECHANISM

Arthur B. Ellery, Akron, Ohio, assignor, by mesne assignments, to Limousine Body Company, Kalamazoo, Mich., a corporation of Michigan

Application September 17, 1932, Serial No. 633,631

3 Claims. (Cl. 292—340)

This invention relates to door latching mechanisms and while it is particularly designed and intended for automobile doors, it will be apparent that the principles of the invention may be more generally applied.

The object of the invention is to improve upon the striker plate with the purpose of obviating squeaks due to the rubbing of the latch against the face of the striker plate. The striker plate is constructed so that a thin film of lubricant is applied to the face of the contacting members which will serve to eliminate the objectionable squeaking, but the construction is so designed that an excess of lubricant is avoided, just sufficient being supplied at all times to accomplish the purpose of the invention. In other constructions in which lubricant is applied to the door latching devices there has been danger of getting too much oil on the parts which will soil the clothes. The present construction obviates this objection for the contacting surfaces are of such nature that oil will not be discharged therefrom but will be retained, and yet the parts will be sufficiently lubricated.

25 In the drawing in which the best known or preferred form of the invention is disclosed,

Figure 1 is a sectional view through a latched door showing the latch and striker plate in engaged position;

30 Figure 2 is a section on the line 2—2 of Figure 1; and

Figure 3 is a detailed perspective view of the striker plate removed from the door.

In the drawing 1 represents the door frame or car body and 2 the door, the former carrying the fixed striker plate 3 and the latter the usual spring-operated bolt 4. The striker plate is shown with the usual primary detent 5 and the main detent 6, which is located at the inner end of the plate, being engaged by the vertical face of the bolt.

The improvement constituting the present invention consists in locating in the face of the main detent a body which covers the greater portion of the face thereof, and which carries within itself a supply of lubricant, which is applied to the face of the latch solely by the rubbing contact of the latch on the striker plate. For this purpose it is preferred to employ a block of wood or other solid and absorbent material 8, which is seated in a recess or pocket 9 in the face of the striker plate, preferably in such fashion that it can be removed and replaced easily should occasion require. For this purpose the socket or recess is preferably dovetailed and the block

slipped into place, being held by contact with the frame of the car and the outer rib 10.

A piece of ash or similar hard absorbent wood has been used effectively for the purpose and this wood is preferably saturated with oil before it is put in position. Other hard but absorbent materials may be used. If desired the upper surface of the striker plate may be provided with a small oil hole 12 through which the oil in the wood may be replenished.

In operation the latch 4 bears against the lubricating block 8 and a slight film of oil will be deposited on the face of the latch. This prevents squeaking and wear of the parts. The oil will also be distributed in a slight degree over the surface of the striker plate as the door is operated, but the amount carried by the latch is necessarily limited and will not be in sufficient quantities to soil the clothing. As the lubricating surface extends over substantially the entire bearing face of the striker plate and constitutes the wearing surface, its action will be more satisfactory than previous devices intended for the same general purpose.

It is to be noted that the block 8 is spaced inwardly from the corner of the striker plate defined by rib 10 which is the corner over which the latch rides into latched engagement with the striker plate and is of the usual comparatively hard wear-resisting, non-chipping metal of the rest of the striker plate, this corner of metal preventing rapid wear of the wood or equivalent insert for retaining the oil.

It will be appreciated that while the description and drawing of the invention have been detailed, such details are not essential to the invention which may be changed or modified without departing therefrom. The block of absorbent and oil retentive material may be located in the latch although the construction shown is preferred.

What is claimed is:

1. In a door latching mechanism, a striker plate having a surface for engagement by a latch, said surface having a recess therein open along one side and defined along its other side and its ends by flanges, certain ones of which have portions that overhang marginal parts of the recess, and a relative hard lubricant retentive element insertable into the recess through its open side, said element being held in said recess by said flanges and by the attachment of said plate to a door frame.

2. In a door latching mechanism, a striker plate having a side surface with detents therein

and an end surface for engagement by a latch, said end surface having a recess therein that is open along that side of the plate opposite said first mentioned side, said recess being defined 5 along its other side and both ends by flanges, certain ones of which include portions that overhang marginal parts of the recess, and a lubricant retentive element insertable into said recess through its open side and being held against 10 displacement in a plane at a right angle to its

insertion by said overhanging portion of said flanges.

3. A door latching mechanism comprising a striker plate having a plane contact surface for the latch, said plate having a dovetailed recess 80 in said surface and a block of absorbent oil retentive wood held in said recess by the attachment of the plate to the door frame.

ARTHUR B. ELLERY.
